EXERCISER

Barney A. Beach, Memphis, Tenn., assignor to Health
Thru Education, Inc., Memphis, Tenn.

Filed Dec. 3, 1970, Ser. No. 26,267

Term of patent 3½ years

Int. Cl. D21—02

U.S. Cl. D34—5

FIG. 1

FIG. 2

FIG. 3

FIG. 1 is a perspective view of an exerciser, showing my new design.

FIG. 2 is a top plan view thereof.

FIG. 3 is a right end elevational of FIG. 1, the left end being substantially similar.

I claim:

The ornamental design for an exerciser, as shown and described.
